(57) **CLAIM**

The ornamental design for a three wheeled single-passenger roadster, as shown and described.

DESCRIPTION

FIG. 1 is a top, front, and left side perspective view of a three wheeled single-passenger roadster showing our new design; FIG. 2 is a left side elevation view thereof; FIG. 3 is a top plan view thereof; FIG. 4 is a rear elevation view thereof; FIG. 5 is a front elevation view thereof; FIG. 6 is a top, rear, and right side perspective view thereof; FIG. 7 is a top and right side perspective view thereof; FIG. 8 is a top, rear, and left side perspective view thereof; FIG. 9 is a rear and left side perspective view thereof; FIG. 10 is a rear and right side perspective view thereof; and, FIG. 11 is a front and right side perspective view thereof. The broken lines in the drawings illustrate portions of the three wheeled single-passenger roadster that form no part of the claimed design.
